UNITED STATES PATENT OFFICE.

HERBERT S. HUMPHREY, OF KALAMAZOO, MICHIGAN.

VALVE MECHANISM.

Application filed August 22, 1924. Serial No. 733,552.

This invention relates to improvements in valve mechanisms.

The main objects of this invention are:

First, to provide an improved thermostatically actuated valve mechanism which is well adapted for use in water heaters and the like.

Second, to provide an improved thermostatically actuated valve in which the valve is opened and closed with a snap action.

Third, to provide an improved thermostatically actuated valve mechanism which is sensitive in its action and at the same time is very strong and durable.

Objects pertaining to details and economies of construction and operation of my improvements will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a side view of a structure embodying the features of my invention, one of the gas pipes being shown in section, a portion 30 of the thermostat being broken away.

Fig. II is an end view looking from the left of Fig. I.

Fig. III is a detail view mainly in section on a line corresponding to line 3—3 of Figs. 35 II and IV.

Fig. IV is a detail section on a line corresponding to line 4—4 of Figs. I and III.

Referring to the drawing, 1 represents the wall of a tank or water heater. 2 is a tubular housing for the thermostat projecting into the tank or heater. The valve casing 3 is provided with inlet and discharge connections 4 and 5. The valve 6 is provided with a stem 7 having tappets 8 threaded thereon 45 for adjustment.

The thermostat consists of a tubular element 9 secured at its upper end to the tubular part 10 of the bracket 11 and the element 12 within the tubular element, the element 12 being preferably a porcelain rod acting upon the thrust member 13 projecting upwardly 50 from the tubular part 10.

The operating connections for the thermostat to the valve consist of a valve lever 14 pivoted at 15 with its swinging end disposed 55 between the tappets 8 on the valve stem.

The rocker 16 is mounted on the pivot 15 and is operatively connected to the lever 14 by means of the thrust springs 17 disposed between the pairs of thrust blocks 18, one 60 thrust block of each pair engaging the lever 14 on opposite sides of its pivot 15, the other engaging the outer ends of the rocker. As the rocker is oscillated it swings the points of engagement of the thrust blocks to opposite sides of the pivot plane of the rocker, thereby actuating the lever 14 with a snap action and yieldingly holding it in either position.

The stop 19 engaging the hole 20 in the 70 rocker limits the throw of the rocker. This rocker is actuated by the actuating lever 21 which is fulcrumed at 22 on the bracket 11, and is provided with fingers 23 and 24 engaging the eccentric lug 25 on the rocker member. The lever 21 is operatively connected to the thermostat by means of the lever 27 which is pivoted at 28 to engage the thrust member 13, the lever 27 being 75 provided with a thrust screw 29 engaging the thrust member 13 and the lever 21 having a thrust screw 30 engaging the end of the lever 27. This provides for adjustment.

The finger 24 is a blade spring and of such strength or tension as to actuate the rocker but will yield on the further throw or excessive throw of the lever 21 under the action of the thermostat. This prevents breakage and also avoids the necessity of 80 very accurate adjustments. The lever 21 is held downwardly by the spring 31 carried by the spring holder 32 and connected to the stirrup 33 embracing the lever.

The spring 31 has threaded engagement 95 with the holder so that the tension of the spring can be adjusted as desired.

My improved thermostatically actuated valve is very sensitive, that is, it can be adjusted to operate practically in slight variations of temperature.

Having thus described my invention what I claim as new and desire to secure by Letters Patent is:

1. The combination with a thermostat and a valve, of a pivoted valve lever connected to said valve, a rocker having an eccentric lug, operating connections for said rocker to said valve lever whereby the lever is actuated with a snap action upon the actuation of the rocker, a stop limiting the throw of said 105 rocker, an actuating lever operatively associated with an element of the thermostat and 110

provided with a pair of fingers coacting with said lug, one of said fingers being a spring adapted to yield on the excessive throw of said actuating lever by the thermostat, and a 5 return spring for said actuating lever.

2. The combination with a thermostat and a valve, of a pivoted valve lever connected to said valve, a rocker having an eccentric lug, operating connections for said rocker to 10 said valve lever whereby the lever is actuated with a snap action upon the actuation of the rocker, and an actuating lever operatively associated with an element of the thermostat and provided with a pair of fingers coacting 15 with said lug, one of said fingers being a spring adapted to yield on the excessive throw of said actuating lever by the thermostat.

3. The combination with a thermostat and 20 a valve, of a pivoted valve lever, a rocker having an eccentric lug, operating connections for said rocker to said valve lever adapted to actuate said valve lever with a snap action, a stop limiting the throw of said 25 rocker, and an actuating lever operatively associated with an element of the thermostat having a part coacting with said lug for actuating said rocker adapted to yield on the excessive throw of said actuating lever by 30 said thermostat.

4. The combination with a thermostat and a valve, of a pivoted valve lever, a rocker

having a pivot axis coinciding with that of said valve lever, a stop limiting the throw of said rocker, pairs of thrust blocks, one block 35 of each pair engaging said lever on the opposite side of its pivot and the other engaging the outer ends of the rocker member, coiled springs coacting with said pairs of thrust blocks, and a thermostat actuated member 40 operatively associated with said rocker whereby the valve lever is actuated with a snap action upon the actuation of the rocker.

5. The combination with a thermostat and valve, of a pivoted valve lever, a rocker having a pivoted axis coinciding with that of said valve lever and operatively associated with said thermostat, and spring actuated thrust members carried by said rocker and 45 engaging said valve lever on opposite sides of its pivot whereby the valve lever is actuated with a snap action upon the actuation of the rocker.

6. The combination with a valve, of a pivoted valve lever, a pivoted rocker, means 55 for actuating said rocker, spring pressed thrust members carried by said rocker and engaging said valve lever on opposite sides of its pivot whereby the valve lever is actuated with a snap action upon the actuation of 60 said rocker.

In witness whereof I have hereunto set my hand.

HERBERT S. HUMPHREY.
